UNITED STATES PATENT OFFICE.

AVERRY E. BLAYLOCK, OF LITTLE ROCK, ARKANSAS.

SIGNAL SYSTEM FOR RAILWAY CARS.

Application filed May 13, 1921. Serial No. 469,379.

To all whom it may concern:

Be it known that I, AVERRY E. BLAYLOCK, a citizen of the United States of America, and resident of Little Rock, in the county of Pulaski and State of Arkansas, have invented certain new and useful Improvements in Signal Systems for Railway Cars, of which the following is a specification.

My invention relates to a safety signal system and attachment adapted to be employed on hand cars or gasoline motor cars used on railroads equipped with an electrical block system of either the charged track section, or bonded rail type.

The primary object of the invention is the provision of a system of circuits including magnets, an armature, a buzzer, and local batteries, adapted to be interchangeably used on either a hand car or gasoline motor car, in which when used on a motor car, the engine circuit is included, so that when a train enters the block occupied by the car, the engine circuit will be broken stopping the car, and the buzzer will sound a warning in either case.

Another object is to provide, in a system of this character, means for rendering the system inoperative without interfering with the engine circuit included therein, when it is desired to use a motor car to trail other cars through the block.

A further object is to provide, in a system of this character, means for testing the system irrespective of the type of block signal system in connection with which the car is operated.

With these, and such other objects in view as will be apparent from the description, my invention resides in the novel construction, combination, and arrangement of parts hereinafter described and claimed, and illustrated in the accompanying drawing, in which;

Fig. 1, is a diagrammatic representation of the circuits and elements of the invention, and

Fig. 2, an elevation of a car illustrating an element employed.

In detail, the invention comprises a car 1 which may be of any preferred type of hand or motor operated, provided with wheels 2 insulated from the axles 3 by means of insulating rings 4, to prevent a short circuit across the rails 5. Mounted on the car body is a pair of trailing contact members 6, held in contact with the rails by means of springs 7. The car engine circuit is dia-

grammatically represented at E of Fig. 1, in which is disposed the usual switch e' from the poles of which lead wires 8 and 9 and in which the engine is indicated by C. 60 M denotes a pair of connected magnets having an armature A carrying an extension X which is normally engaged against a pair of contacts 10 and 11 through the action of a retractile spring S. Contacts 10 and 11 are adjustably mounted in posts 12 and 13 respectively, and arranged on the opposite side of the extension X, is a pair of contacts 14 and 15 carried in posts 16 and 17 and adapted to be engaged by the extension X 70 when the magnets are energized.

B designates signal means comprising in this instance a buzzer, having a local battery G. An additional battery H is arranged in the system as hereinafter described. A series of knife switches J, K, L, O, P, R, T and U, are arranged in the system in connection with the various elements by means of wires j, j', k, k', l, l', o, o', p, p', r, r', t, t', u and u', which lead respectively from the switch points. The magnets are in connection with the system by means of wires m and m', and the rail contact members 6 are likewise connected by wires 6' and 6".

In Fig. 1, I have illustrated the system as in use on a car occupying a block using the bonded rail system and in which current is fed from the local battery H on the car. In this system, the switches O, P and R are closed, leaving all others open. The magnets M are normally deenergized and the engine ignition circuit (disregarding the direction of the current) is from the battery in the E circuit over wire 9, wire o', switch O, wire o, wire 13', post 13, across X, post 12, wire 8 and return, the car proceeding without interruption. When a train enters the block, a circuit is completed through the wheels and axles of the train and the rails through contacts 6 throwing local battery H into circuit, energizing magnets M, breaking the engine circuit to stop the car, and operating the buzzer. The magnet circuit will be as follows; battery H, wire H', wire m, magnets M, wire m', wire 6'', one rail, wheels and axles of the truck of the train in advance, the other rail, wire 6', wire p, switch P, wire p', back to H. Armature A is drawn down, breaking the engine circuit and closing the buzzer circuit which is as follows; battery G, buzzer B, wire b'', post

17, across X, post 16, wire r, switch R, wire r', back to G.

When the car is used in a block system using charged track sections, where the current is fed from the rails to the car from the block system batteries, switches J, K, and L, are to be closed, leaving all others open. The magnets M are then normally energized, with armature extension X bridging contacts 14 and 15. The magnet circuit will be as follows; from rail to wire 6", wire m', M, wire m, wire k', switch K, wire k, wire 6', to other rail, using the block system current. The engine circuit will be as follows; wire 8, post 17, across X, post 16, wire j', switch J, wire j, wire 9 and return, the car proceeding without interruption. When a train enters the block, the contacts 6 will be short circuited, deenergizing the magnets. Armature X raises by action of spring S, breaking the engine circuit at 14 and 15, and stopping the car. Contacts 10 and 11 will then be bridged closing the local circuit of the buzzer, which is as follows; battery G, buzzer B, wire b', post 12 (across X, post 13, wire 13', switch L, wire l', back to G, sounding an alarm.

Should it be desired to test the device while running in either type of block signal system, switch U is closed. In the arrangement shown in Fig. 1, when U is closed, magnets M are energized, circuit being from battery H, wire k', wire m, magnets M, wire m', wire u', switch U, wire u, wire p, switch P, wire p', back to H. The engine circuit will be broken at 10 and 11, stopping the car, and the buzzer will sound, the circuit being from battery G, buzzer B, wire b", post 17, across X, post 16, wire r, switch R, wire r' back to G.

On a charged track section system, where switches J, K, and L are closed, when switch U is closed, the same results will be accomplished. Contacts 6 will be short circuited through wires u, u' and U, deenergizing the magnets, breaking the engine circuit at 14 and 15, and operating the buzzer. Buzzer circuit in this instance, will be from battery G, buzzer B, wire b', post 12, across X, post 13, wire 13', wire l, switch L, wire l', back to G.

When it is desired to use the car to trail other cars over the block, switch T is closed, leaving all others open. The engine circuit

will then extend over wire 8, wire t, switch T, wire t', wire 9, and return, the car being free to proceed without interference from the cars trailed.

It will be understood that when the attachment is used on a manually operated hand car, wires 8 and 9 are left out, the system operating respective to the buzzer in the manner as described. When the device is operated upon a gas engine propelled car, it will be understood that the switch e' will be left open unless it is desired to eliminate the automatic control.

While I have described and illustrated certain elements and arrangements thereof, which enter into the construction and operation of my invention, I desire it to be understood that I do not limit myself to these, but that any such may be used as will fall within the scope of the invention as claimed.

I claim:—

1. In association with an electrical block rail system, the combination of a motor driven vehicle having a motor circuit, the wheels of said vehicle that contact one rail being insulated from the wheels that contact the other rail, and a safety device comprising an electrical alarm and a control device, said control device being operated by the short circuiting of the rails and comprising circuit making and breaking elements adapted to close the alarm circuit and open the motor circuit upon said short circuiting of the rails.

2. In association with an electrical block rail system, the combination of a motor driven vehicle having a motor circuit, the wheels of said vehicle contacting one rail being insulated from the wheels contacting the other rail and an electrical safety device comprising an alarm, an independent source of current to operate the alarm, and a control device operated by the short circuiting of the rails, said control device comprising means for opening the motor circuit and closing the alarm circuit and means associated with said control means for testing its operation independently of the short circuiting of the rails.

AVERY E. BLAYLOCK.
